UNITED STATES PATENT OFFICE.

CHARLES M. KELLOGG, OF CHETEK, WISCONSIN.

VEHICLE-SEAT.

SPECIFICATION forming part of Letters Patent No. 513,939, dated January 30, 1894.

Application filed June 9, 1893. Serial No. 477,034. (No model.)

To all whom it may concern:

Be it known that I, CHARLES M. KELLOGG, of Chetek, in the county of Barron and State of Wisconsin, have invented a new and useful Improvement in Vehicle-Seats, of which the following is a full, clear, and exact description.

My invention relates to an improvement in vehicle seats, and it has for its object to so construct the vehicle seat that the lazy-back section thereof will have a hinged connection with the back proper of the seat, and furthermore whereby the lazy-back section will be connected with spring cushioned slides, where- 15 by when a person exerts rearward pressure against the lazy-back section, the section will fall back against the tension of the spring cushions to a predetermined degree, returning to its normal or upright position automatically when released from pressure.

A further object of the invention is to provide a vehicle seat which will be exceedingly comfortable, enabling a person to assume practically whatever position he may desire 25 with reference to the inclination of the body, in order to accommodate himself to the road over which he may be traveling.

The invention consists in the novel construction and combination of the several parts, as 30 will be hereinafter fully set forth and pointed out in the claim.

Reference is to be had to the accompanying drawings forming a part of this specification, in which similar figures and letters of reference indicate corresponding parts in all the 35 views.

Figure 1 is a rear elevation of the vehicle seat having the improved back applied thereto. Fig. 2 is an end view thereof. Fig. 3 is 40 a plan view of a portion of a seat, and likewise a plan view partly in section, of the cushion attachment to the seat. Fig. 4 is a horizontal section through the cushion attachment, the said section being taken practically 45 on the line 4—4 of Fig. 3; and Fig. 5 is a transverse section through the cushion attachment, taken practically on the line 5—5 of Fig. 4.

In carrying out the invention the vehicle 50 seat proper A, may be of any desired shape or of any approved construction. The lazy-

back B, may likewise be of any well known form, and may be made to approach the back proper of the seat more or less closely. The lazy-back section of the seat is connected with 55 the main back section by means of hinges 10, of any approved description. Ordinarily, however, each of the hinges consists of a link or bar securely fastened to the rear of the lazy-back section, and the lower ends of the 60 link or bar are pivotally connected with the rear of the main back section, as shown at 11 in Figs. 1 and 2. Usually two hinges are employed, one of them being located at each side of the center of the back.

65 A cushion attachment C, is located upon each end of the seat. This cushion attachment is adapted to be attached to the end portions of the lazy-back. Each cushion attachment consists of a casing 12, which casing is 70 sometimes made as shown in the drawings, in two sections 12^a and 12^b. Both sections are made substantially flat upon their rear faces, and their body portions are cylindrical in cross section, or practically so, and said body 75 portions are hollow. The section 12^b of the casing is adapted to fit over one end of the section 12^a, and both of these sections at their outer ends are usually provided with lugs 13, through which screws or like fastening de- 80 vices are passed for the purpose of securing the attachment to the vehicle seat. In the end of the casing which is adapted to be capped by the section 12^b a slot 14, is produced in its upper and lower surfaces, the slots being in 85 vertical alignment; and within the section 12^a of the casing which contains the slots a spring 15, of any desired character, is located. The spring ordinarily employed is a coiled spring, as shown in Figs. 3 and 4; and the spring has 90 bearing against one end of the casing, while at its opposite end it bears against or is attached to a slide 16, loosely fitted in the casing section 12^a, which slide is provided with guide projections 16^a, adapted to travel in the 95 casing slots 14. The casing is secured to either the outer side surface of the ends of the seat, or to the top edge of said ends, according to the character of the connection between the casing and the lazy-back; or in 100 other words, the position of the casing is regulated according to the shape of the arm rests

17 of the seat. After the slide 16, has been placed in the section 12^a of the casing, the open end of said casing is closed by a plug 18, which is secured therein in any suitable or 5 approved manner. Whenever it is desirable to remove the spring and slide, the two sections of the casing are separated and the plug 18 is withdrawn, whereupon the slide and spring may be readily taken out through the 10 open end of the section in which they are located. The arm rests 17, are usually secured to the end portions of the lazy-back section, and are curved forwardly and downwardly until their lower ends are passed through the 15 slide 16, preferably at its widest point; and the lower extremities of the arm rests may then be secured in position by a lock nut or the equivalent thereof. Thus in operation it will be observed that when pressure is exerted in a rearwardly direction upon the lazy-back, the back may be forced rearward to the 20 full extent of the possible compression of the springs 15; or it may be carried back gradually to its full rearward throw, or may be 25 stopped at any point forward thereof. It is also evident that as soon as back pressure is

removed from the lazy-back section it will automatically return to its upright position.

Having thus described my invention, I claim as new and desire to secure by Letters 30 Patent—

The combination with a vehicle seat, and a back having a hinged connection with the seat, of side arms connected at one end with the seat, and spring devices acting on the forward ends of said arms, and consisting each of a cylindrical casing comprising a main section slotted at diametrically opposite points and an end cap therefor each provided with end lugs having flat rear faces and apertured 40 for receiving screws or the like, a block fitted on the main section and provided with guide projections fitting in the slots of the casing, the side arms of the seat being secured to the said blocks, and a plug fitting the end of the 45 main section, said end being received in the cap section, substantially as described.
